LOOP SLIDE BUCKLE

Application filed November 27, 1931. Serial No. 577,462.

This invention relates to loop slide buckles adapted to adjustingly connect a strap to a button provided by a garment thereby to be supported.

5 The objects of the invention are to provide a loop slide buckle the slide buckle member of which is adapted to sufficiently bight a single strand of strap threaded into the buckle to hold the same during a pulling 10 strain thereon along the plane of the device in a direction opposite to that of an opposing strain upon the loop member; to provide a two member loop slide buckle of which the slide buckle member is made of sheet-metal 15 and the loop member of wire; to provide, for separate or such combined use, a slide buckle member of such structure that a strap threaded therein is positively secured; and to provide such combined members with a looped 20 connection adapted to maintain, under a pulling stress, the normally contracted condition of the loop member. With these and other objects in view, as may hereinafter appear from that which is herein pointed out 25 and illustrated by the drawing, the structure as described may be modified to include that which is within the scope of what hereinafter may be claimed.

To understand the character of the invention, reference is made to one illustrative device illustrated by the accompanying drawing in which the Figure 1 is an upright face elevation of the device; and the Figure 2 is an edge view of the device illustrating, in 35 dotted lines, a strap threaded therein.

Referring more particularly to the drawing, the device, being preferably made in two parts, comprises the slide buckle and button loop members 1 and 2, respectively. The 40 slide buckle member 1 is preferably made of sheet-metal, but may be made of wire if desired. In sheet-metal form the member 1 is stamped out in substantially rectangular form having the loops 3, 4 and 5, the metal 45 from within the loops 3 and 5, instead of being wholly cut out therefrom, is bent out of the plane of the body portion of the member 1, such metal extending in opposite directions to provide the projections 6 and 7 at substantially right angles to each of the in-

termediate bars 8 and 9, respectively, formed by the cutting of the said loops 3, 4 and 5. While each of the projections 6 and 7 is illustrated as having the continuous cut-metal edges 10 and 11, these cut-metal edges 10 and 55 11 may be scalloped or otherwise formed as illustrated and described in a previous application filed by your petitioner October 21, 1931, Serial Number 570,083. The bottom bar 12 of the member 1 is provided with the spaced depressions 13 and 14. The button loop member 2 is preferably made of wire, but may be stamped out as an integral part of the member 1. As made of wire, however, 60 a middle portion of a piece of wire is bent to form the button-retaining loop 21 and the button-receiving loop 20 both axially associated and having between them the contracted throat portion 22, the remaining end 65 portions of the wire being bent to partially form the suspension loop 23, and, to assemble the members 1 and 2, the looped extremities 24 and 25 of the button loop member 2 are made to loosely engage around the bottom 70 bar 12 of the slide buckle member 1 at each of the spaced depressions 13 and 14, respectively. 75

In use, an end of the strap S is passed into the loop 3 from the rear of the slide buckle as illustrated, around the intermediate bar 8 and against its cut-metal edges 10 and 11, then into the loop 4 from the face of the slide buckle and around the intermediate bar 9 and against its cut-metal edges 10 and 11, 80 then the strap is passed into the loop 5 from the rear of the slide buckle and over the bottom bar 12, the end of the strap S being passed into the suspension loop 23 from the face of the slide buckle to repose behind the 85 button loop member 2. The abrupt contours of a single strand of strap S threaded into the slide buckle member 1 and augmented by the contact of the strap S with the cut-metal edges 10 and 11 of both intermediate bars 8 and 9 insures the strap S against slipping unintentionally within the slide buckle member 1. The resting of the looped extremities 24 and 25 of the button loop member 2, each within a depression 13 or 14 of 90 the bottom bar 12 of the slide buckle member 95 100

1, maintains the normally contracted condition of the throat portion 22 of the button loop member 2; for, upon the expansion of the throat portion 22, the looped extremities 5 24 and 25 have a tendency to ride up out of the depressions 13 and 14 but only to be returned therein by the resiliency of the button loop member 2 augmented by the opposing pulling stress placed upon the members 10 1 and 2 when supporting a garment.

I claim:—

1. A loop slide buckle, the combination of a substantially rectangular sheet-metal frame having spaced intermediate bars with cut-metal edges, a cut-metal edged portion of each bar being bent perpendicularly to the plane of the frame, said bent portions projecting from said plane in opposite directions, one from the other, and a button loop 15 axially associated with said frame in said plane.

2. A loop slide buckle comprising a substantially rectangular sheet-metal buckle frame having three axially associated loops 20 in a common plane and divided by two intermediate bars with cut-metal edges, a cut-metal edged portion of each bar being bent perpendicularly to said plane and projecting in opposite directions one from the other, 25 and a button loop axially associated with the said frame in said plane.

3. A loop slide buckle comprising a substantially rectangular sheet-metal frame having top, bottom and side bar portions and 30 spaced intermediate bars with cut-metal edges, a cut-metal edged portion of each intermediate bar being bent perpendicularly to the plane of said frame and projecting in opposite directions one to the other, the bottom bar portion of said frame having spaced depressions around which the looped extremities of a wire button loop member pivotally 35 engage.
